UNITED STATES PATENT OFFICE.

WILLIAM COLWELL, OF CHILlicothe, ILLINOIS, ASSIGNOR TO THE JOLIET MANUFACTURING COMPANY, OF JOLIET, ILLINOIS.

CORN-SHELLER.

SPECIFICATION forming part of Letters Patent No. 595,765, dated December 21, 1897.

Application filed February 24, 1896. Serial No. 580,487. (No model.)

To all whom it may concern:

Be it known that I, WILLIAM COLWELL, a citizen of the United States, residing in Chillicothe, in the county of Peoria and State of Illinois, have invented a new and useful Improvement in Corn-SHELLERS, of which the following is a specification.

This invention relates to improvements in corn-shellers of the kind known as "cylinder-shellers."

The invention enables me to accomplish a very much larger amount of work than is possible with the best shellers heretofore on the market, the increase being some twenty to twenty-five per cent., and while it should be classed as a cylinder-machine it nevertheless differs from other cylinder-machines in important respects.

In my improved machine the part corresponding to the cylinder of the old machines is composed of a series of hubs or rings mounted side by side upon a common shaft, and each hub is armed with two wings or beaters projecting outwardly from its opposite sides. These wings or beaters are considerably longer in a radial direction than are the studs or ribs previously employed with the drum-cylinders, and I prefer that they should be about two and a quarter inches in length, measuring from the outer surface of the hub to the tip of the beater, as I find excellent results to attend the use of beaters of that radial length. The beaters, or a portion of them, are arranged so they may serve, in addition to their primary function of effecting, either directly or indirectly, the shelling of the corn, the further function of feeding the corn along the series of beaters. This arrangement preferably consists in locating the beaters at the initial or feeding end of the shelling mechanism in spiral lines, whereby they are adapted to act as force-feeding devices and prevent any accumulation of ears at the entrance to the shelling mechanism. The individual

beaters thus arranged spirally are also preferably made to stand with their flat sides inclined to the axial line of the hubs, so that when they strike an ear they will naturally force that ear toward the rear end of the shelling mechanism, as well as in a circular direction corresponding to the rotary movement of

the beater itself. One or more pairs of the beaters at the rear or discharge end of the series are also similarly arranged or inclined, so they may force the denuded ears out from the inclosing cage surrounding the revolving beaters. The intermediate series of beaters—that is, those between the feeding-beaters at the receiving end and the discharging-beaters at the discharging end—are preferably arranged with their flat sides parallel with the axis of the beaters, so that such beaters may perform their primary function of shelling perfectly without any such urging of the ears toward the discharge as will prevent their being perfectly shelled.

In combination with the series of revolving winged hubs above described is a casing or cage surrounding the series of hubs. This casing is composed of closed ends and a longitudinal grating consisting of wires or rods arranged in parallel positions lengthwise of the grating and at short distances apart and circular supporting-bars having openings through which the rods or wires are passed, the casing being thus adapted to permit the passage through it of the shelled corn, and the rods being also adapted to assist in stripping the ears as the latter are rolled or moved over them. The casing is provided with a large feed-opening at one end and a comparatively small discharge-opening at the other end, and the latter is regulable, so that the ears may be prevented from issuing before they are entirely stripped of kernels. The regulable discharge also enables the operator to change the discharge-opening to answer the demands of the particular body of corn being shelled, the adjustment being determined by circumstances, such as the size of the ears or their dampness, dryness, &c.

The invention further relates to other details of construction of the machine, which are fully set forth in the description given below.

In the accompanying drawings, which form a part of this specification, Figure 1 is a side elevation of a machine embodying my invention. Fig. 2 is a longitudinal vertical section. Figs. 3 and 4 are cross vertical sections on the lines 3 3 and 4 4, respectively, of Fig. 2; and Fig. 5 is a horizontal section through

the shelling devices. Fig. 6 is a plan of the main shaking-shoe, and Fig. 7 is an enlarged section of the shelling devices.

My improved sheller is adapted to be mounted upon wheels, so that it can be readily moved about as desired, and I have shown it in Fig. 1 as mounted upon wheels A A.

The corn is fed to the machine by the elevator B, which may contain a force-feed chain of any ordinary construction and be operated by the shaft B'. Said elevator delivers the corn to a hopper C, from which it falls directly into the shelling mechanism. The latter consists, as already stated, of a series of wide wings or hubs D, mounted upon a shaft D', driven by the pulley D². Said shaft is arranged horizontally and longitudinally, being supported by bearings D³ and D⁴. The hubs D are each provided with two wings or beaters projecting some two and a quarter inches beyond the periphery of the hubs. The wings or beaters of the first four or five hubs at the feed end are arranged diagonally or inclined relative to the axis, so that they may urge the corn along toward the other end of the shelling mechanism. I also prefer to arrange these inclined beaters or stirrers in four spiral lines, which is done by placing the beaters alternately in advance of one another, the several beaters being thus enabled to carry forward or continue the feeding action of the previous beaters. The beaters arranged diagonally and spirally in this manner are indicated by D⁵. The beaters or stirrers D⁶ of the next few hubs are arranged in alternate order directly in line with one another and parallel with the axis, as plainly seen at Fig. 2, thus forming four rows of detached wide beaters, and the beaters or stirrers of the last hub are placed diagonally, as indicated at D⁷, so that they may serve to throw out the shelled ears from the cage.

The cage which surrounds the major portion of the rotating beaters or stirrers consists of closed ends and a series of longitudinal rods D⁸, arranged parallel to each other and at distances apart sufficient to permit the free passage of the shelled corn between them, and they are supported in circular bars D⁹. These rods encircle the beaters with the exception of the top, which is formed for a portion of the length of the cover D¹⁰, the remainder of the length being covered by the hopper C.

I prefer to make the beaters or stirrers about nine inches from tip to tip and the surrounding cage about fifteen inches in diameter, so that a comparatively large space will be left between the tips of the beaters or stirrers and the inside of the cage, through which the corn may feed freely and in which the ears may be forced to rub against each other and against the rods of the cage, as already described. This open space should average about three inches in diametrical directions along the top and two inches at the bottom, the shaft D' being set below the cen-

ter of the casing, as plainly shown in the enlarged section, Fig. 7. The action upon the corn caused by the employment of this large shelling-space is different from that taking place in machines where the entire space is contracted to the size or under the size of the ear and in which the ears are shelled by being rolled between the rotating cylinder and the surrounding case. In my invention the ears whenever they get into the lower part of the casing are brought within range of the beaters, so that they are sure to receive numerous blows therefrom and be urged against the casing. They are stripped of their corn by the combined action of the beaters and casing and by the rubbing one against another brought about by the beaters. The length of the beaters or stirrers is about two and one-quarter inches and is much greater than the teeth ordinarily employed in the shelling part of the machines, so that they are better adapted to strike blows than are the short studs upon ordinary cylinders and also better adapted to keep the body of ears in the shelling-space in a constant state of agitation.

At the rear end of the cage is a discharge-opening D¹¹, located below the beater-shaft and provided with an adjustable gate or regulating device D¹², whereby the size of the opening may be increased or reduced, as occasion requires. If the ears display any tendency to leave the cage before the corn is all shelled from them, they can be retained longer in the cage and until the corn is all shelled off by simply reducing the size of the opening, and at the same time any clogging or undue accumulation of ears in the cage may be obviated by making the opening D¹¹ larger.

The ears pass from the opening D¹¹ onto a shoe E, through which the loose kernels of corn drop onto an inclined platform E', attached to the shoe, and are by it conducted into a lower shoe F, located directly under the cage and receiving the main current of the shelled corn therefrom. These shoes E and F are both agitated and are pivoted to the opposite ends of four arms G, the shoe E having an extended frame E² for this purpose. One pair of arms G is mounted upon a shaft G', extending across the machine, and this shaft is actuated so as to swing the arms at both sides of the shoes by means of a crank and pitman G² G³, and the pitman is actuated by an eccentric, the strap or band whereof is shown at G⁴ upon the shaft G⁵, driven by a chain G⁶, receiving power from a cross-shaft G⁷, driven by gears from shaft D.

From the shoe F the corn drops onto platform H and is discharged into the trough H'. A fan J delivers a blast through the falling corn as it drops into shoe F and from said shoe onto the platform H and drives out the chaff and dust therefrom. The upper portion of the case of the fan is extended some distance under the shelling-cage, as shown, so

as to direct the air horizontally across the shoe F, and in order that the current may be kept away from the shoe E and its platform E', I place in front of those parts the deflector or guard K, the construction of which will be understood from Figs. 2, 3, and 6. It is adapted to deflect most of the fan-blast which strikes it downward, and as will be understood from what has already been said it prevents any of the blast from reaching the under surface of the shoe E.

The cobs when discharged from the shoe E fall into the hopper L at the lower end of the cob-stacker L' and are by the latter carried away by the machine. The grain falling into the trough H' may be conducted by the conveyer in said trough to the elevator M and by the latter be elevated for loading in wagons. Power may be given to the machine either through the pulley D², already mentioned, or through the pulley O upon the transverse shaft P, which gears with shaft D', as plainly shown.

The feed-hopper opening above the beaters is very large, as shown, being about the width of the casing in one direction and over a third of the length of the casing in the other direction, so that the ears are freely admitted, and any tendency they may display to arch or bridge over and lodge at the entrance is obviated. It is difficult to show the location of the beater-shaft relative to the casing in drawings made upon so small a scale as that of the main figures, and hence I have added an enlarged section in Fig. 7 to bring out this feature clearly.

I claim—

1. The corn-sheller having shelling devices operating on the principle of shelling the corn by subjecting the ears of corn to a rapid beating, tumbling and stirring action in a confining-chamber in which the corn-ears are loose and free to be knocked, stirred and tumbled in different directions, and comprising in combination a cylindrical casing or grating having a large unobstructed chamber or interior to receive and confine the corn-ears in a loose condition and free to be knocked, stirred and tumbled in different directions by action of rapidly-revolving beaters, and a rapidly-rotating shaft extending centrally in and lengthwise of said casing and provided with a series of radial arms or beaters located at intervals longitudinally along said shaft and at intervals radially about said shaft with wide open spaces between them longitudinally and radially of the shaft to permit the corn-ears to pass in different directions between contiguous beaters longitudinally or radially, the open space between the shaft and said casing or grating being large and unobstructed to permit the corn-ears to be freely knocked, stirred and tumbled in different directions by action of said beaters, whereby the corn is rapidly and perfectly shelled without mutilation of the kernels or grains, said beaters or arms being in a number of separate pieces

from said shaft and having a series of hubs surrounding the shaft to secure the same thereto, substantially as specified.

2. The corn-sheller having shelling devices operating on the principle of shelling the corn by subjecting the ears of corn to a rapid beating, tumbling and stirring action in a confining-chamber in which the corn-ears are loose and free to be knocked, stirred and tumbled in different directions, and comprising in combination a casing or grating having a large unobstructed chamber or interior to receive and confine the corn-ears in a loose condition and free to be knocked, stirred and tumbled in different directions by action of rapidly-revolving beaters, and a rapidly-rotating shaft extending centrally in and lengthwise of said casing and provided with a series of radial arms or beaters located at intervals longitudinally along said shaft and at intervals radially about said shaft with wide open spaces between them longitudinally and radially of the shaft to permit the corn-ears to pass in different directions between contiguous beaters longitudinally or radially, the open space between the shaft and said casing or grating being large and unobstructed to permit the corn-ears to be freely knocked, stirred and tumbled in different directions by action of said beaters, whereby the corn is rapidly and perfectly shelled without mutilation of the kernels or grains, a portion of said beaters at the feeding end of said casing or grating having their faces inclined to the shaft, and the beaters at the middle portions of said casing or grating having their faces parallel to the shaft, substantially as specified.

3. The corn-sheller having shelling devices operating on the principle of shelling the corn by subjecting the ears of corn to a rapid beating, tumbling and stirring action in a confining-chamber in which the corn-ears are loose and free to be knocked, stirred and tumbled in different directions, and comprising in combination a casing or grating having a large unobstructed chamber or interior to receive and confine the corn-ears in a loose condition and free to be knocked, stirred and tumbled in different directions by action of rapidly-revolving beaters, and a rapidly-rotating shaft extending centrally in and lengthwise of said casing and provided with a series of radial arms or beaters located at intervals longitudinally along said shaft and at intervals radially about said shaft with wide open spaces between them longitudinally and radially of the shaft to permit the corn-ears to pass in different directions between contiguous beaters longitudinally or radially, the open space between the shaft and said casing or grating being large and unobstructed to permit the corn-ears to be freely knocked, stirred and tumbled in different directions by action of said beaters, and the open space or distance between the outer ends of said beaters and said surrounding casing or grating being large and sufficient to permit corn-ears to pass be-

tween the same, whereby the corn is rapidly and perfectly shelled without mutilation of the kernels or grains, substantially as specified.

- 5 4. The corn-sheller having shelling devices operating on the principle of shelling the corn by subjecting the ears of corn to a rapid beating, tumbling and stirring action in a confining-chamber in which the corn-ears are loose

10 and free to be knocked, stirred and tumbled in different directions, and comprising in combination a cylindrical casing or grating having a large unobstructed chamber or interior to receive and confine the corn-ears in

15 a loose condition and free to be knocked, stirred and tumbled in different directions by action of rapidly-revolving beaters, and a rapidly-rotating shaft extending centrally in and lengthwise of said casing and provided

20 with a series of radial arms or beaters located at intervals longitudinally along said shaft and at intervals radially about said shaft with wide open spaces between them longitudinally and radially of the shaft to permit

25 the corn-ears to pass in different directions between contiguous beaters longitudinally or radially, the open space between the shaft and said casing or grating being large and unobstructed to permit the corn-ears to be

30 freely knocked, stirred and tumbled in different directions by action of said beaters, whereby the corn is rapidly and perfectly shelled without mutilation of the kernels or grains, said surrounding casing or grating

35 having an opening at its end for the discharge of the cobs, and one pair of said beaters adjacent to said opening having their faces at an angle to said shaft to aid in discharging or forcing the cobs through said opening, substantially as specified.

40 5. The corn-sheller having shelling devices operating on the principle of shelling the corn

5. The corn-sheller having shelling devices operating on the principle of shelling the corn

by subjecting the ears of corn to a rapid beating, tumbling and stirring action in a confining-chamber in which the corn-ears are loose and free to be knocked, stirred and tumbled in different directions, and comprising in combination a casing or grating having a large unobstructed chamber or interior to receive and confine the corn-ears in a loose condition and free to be knocked, stirred and tumbled in different directions by action of rapidly-revolving beaters, and a rapidly-rotating shaft extending centrally in and lengthwise of said casing and provided with a series of radial arms or beaters located at intervals longitudinally along said shaft and at intervals radially about said shaft with wide open spaces between them longitudinally and radially of the shaft to permit the corn-ears to pass in different directions between contiguous beaters longitudinally or radially, the open space between the shaft and said casing or grating being large and unobstructed to permit the corn-ears to be freely knocked, stirred and tumbled in different directions by action of said beaters, whereby the corn is rapidly and perfectly shelled without mutilation of the kernels or grains, a portion of said beaters at the feeding ends of said casing or grating having their faces inclined to the shaft, and the beaters at the middle portions of said casing or grating having their faces parallel to the shaft, said surrounding casing or grating having an opening at its end for the discharge of the cobs, and one pair of said beaters adjacent to said opening having their faces at an angle to said shaft to aid in discharging or forcing the cobs through said opening, substantially as specified.

WILLIAM COLWELL.
